(57) **CLAIM**

The ornamental design for a socket for LED tube-lamp, as shown and described.

DESCRIPTION

FIG. 1 is a perspective view of a socket for LED tube-lamp showing my new design;

FIG. 2 is another perspective view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a left elevation view thereof; and,

FIG. 8 is a right elevation view thereof.
